J. H. OPTENBERG.

FLANGING CLAMP.

APPLICATION FILED FEB. 24, 1903.

NO MODEL

UNITED STATES PATENT OFFICE.

JOHN HENRY OPTENBERG, OF SHEBOYGAN, WISCONSIN.

FLANGING-CLAMP.

SPECIFICATION forming part of Letters Patent No. 729,959, dated June 2, 1903.

Application filed February 24, 1903. Serial No. 144,573. (No model.)

To all whom it may concern:

Be it known that I, JOHN HENRY OPTENBERG, a citizen of the United States, and a resident of Sheboygan, in the county of Sheboygan and State of Wisconsin, have invented certain new and useful Improvements in Flanging-Clamps; and I do hereby declare that the following is a full, clear, and exact description thereof.

10 My invention relates to clamps intended especially for use in forming flanges on boiler-plate or heavy sheet-iron and the like; and it consists in certain peculiarities of construction and combination of parts, as will be fully 15 set forth hereinafter in connection with the accompanying drawings and subsequently claimed.

In the said drawings, Figure 1 is a view in side elevation of my improved clamp, partially 20 broken away or in section to better illustrate certain details of construction. Fig. 2 is a detail plan view of one end of the device with the handle-nut and upper end of the screw removed. Figs. 3 and 4 are vertical sectional 25 detail views, both taken on the line 3 4 in Fig. 1, but looking in opposite directions, as indicated by the arrows. Fig. 5 is a detail view of a portion of the upper part of one of the end standards, drawn to an enlarged scale 30 and showing the opposite side from that shown in Fig. 1. Fig. 6 is a detail sectional view of the same taken on the line 6 6 in Fig. 5.

Referring by numerals to the said drawings, 1 2 represent the end standards, the upper 35 ends of which standards are forked or bifurcated to receive the ends of the two sections of the clamp proper, the lower section 3 being stationary and secured to the end standards by the bolts 4 4 and nuts, as shown, and the upper section 5 being vertically movable 40 within the said upper ends of the end standards, which thus form guideways. The upper section 5 has vertical depending guide-strips 6 6, secured in pairs adjacent to each 45 end thereof by bolts 7 7, which strips straddle the lower section 3 close to the inner faces of the end standards 1 2 and which strips are further formed with series of holes 8 8 there-through, those in one strip being in line with 50 those in the opposite strip of each pair.

The opposed faces of the sections 3 5 are cut away at each end to form the horizontal

recesses 9, and the ends of the upper section 5 are forked, so as to leave open slots or recesses 10, communicating with the said recesses 9, these recesses being for the reception of the bell-crank levers 11 and the screws 12, projecting from the upper end of one arm of each lever and rigid or integral therewith, the upper end of each screw terminating in a reduced round tip 13. These levers are laterally enlarged at the junction of their two arms, as shown at 14, and transversely perforated therethrough, whereby they are secured in place by the pivot-bolts 15, while the inner end of the lower arm of each lever has pivotally secured thereto a pair of rollers 16 16. A foot-lever 17 projects from the upper arm of each lever, and in addition a hand-lever 18 is adapted to fit over the tip 13 of the lever-screw 12. 19 19 are the handle-nuts, which engage with the screws 12 12.

The bifurcated upper ends of the standards 1 2 are formed with registering series of transverse holes therethrough for the reception of the said pivot-bolts 15, the holes through one side being simply cylindrical bores 20 20, while those through the opposite side and which are marked 21 21 are each partly closed by a semi-annular stop 22. Each pivot-bolt 15 80 has a central projection 24 at one end of reduced diameter, the outer end of which is fitted with another semi-annular stop or flange 23, while the opposite end of the said pivot-bolt 15 is formed with a heavy bent portion 85 25. The upper clamp-section 5 is provided with a clevis 26 for lifting the clamp with a crane when necessary.

Heretofore with the flanging-clamps in general use the upper section has been generally raised and lowered by means of screws operated by hand-power, and one great objection has been the length of time required for adjustment and change of the sheet-iron or heavy boiler-plate on which straight 95 flanges are to be turned, as often the material, particularly heavy plate, which must be heated for the flanging operation, would get cold before getting same in proper position in the clamp for bending, whereas my present device is very quick in operation. When the parts are in the position shown in Fig. 1, in order to receive the work the levers 11 (with their screws 12) are pulled downward

by the foot-levers 17 or hand-levers 18, or both, which action will raise the upper clamp-section 5 by means of the inner or lower arms of said bell-crank levers 11 to admit of the plates 5 or other work to be flanged being placed on the lower clamp-section 3, and then the upper section 5 is instantly brought down upon said work or material by throwing the levers 11 up or back to their former position, with the 10 screws 12 in upright position, and the handle-nuts 19 are turned till they engage with the top of the upper section 5, and the work is thereby quickly and securely clamped ready for bending.

15 In order to vary the distance between the opposed faces of the clamp-sections 3 5, according to the shape or thickness of the material to be flanged, the pivot-bolts 15 are removed and the levers 11 are raised or lowered, as required, until the transverse bores through the levers are in line with the proper holes 20 21, and then the pivot-bolts 15 are inserted to secure them in their adjusted positions. In order to withdraw the said pivot-bolts 15, they are given a half-turn, so that 25 their end flanges 23 will be free from engagement with the upper stops 22 of the holes 21, when they can be pulled out, and when replaced in their adjusted position the weighted ends 25 will serve to keep the flanges 23 uppermost and against the stops 22 just named, thus providing a quick and automatic lock. If it is desired when the upper section 5 has 30 been raised to retain it in that position while the pivot-bolts 15 are being changed, then pins can be thrust through the proper holes 8 in the guide-strips 6, so that said pins will rest on the upper face of the lower clamp-section 3 until said pins are removed. If, 35 however, there is not to be any change in the location of the levers 11 for the next operation, it is only necessary (after the handle-nuts 19 have been loosened) to drop the screws 12 to the fullest extent, so that their 40 outer ends shall incline below a horizontal line and with the foot-levers 17 bearing against the outer surfaces of the end standards, and then the upper clamp-section 5 will remain in its raised position until the 45 levers 11 are again moved.

Having thus described my invention, what I claim as new, and desire to secure by Letters Patent, is—

1. In a flanging-clamp, the combination with 55 a pair of end standards, having forked or bifurcated upper ends, of a lower clamp-section immovably secured to said end standards; an upper clamp-section, formed with open slotted ends having vertical movement in the 60 forked upper ends of the standards; bell-

crank levers pivoted to the end standards, for raising the said upper clamp-section, screws rigid with and extending from said levers through said open slotted ends of the upper clamp-section, and clamping-nuts on said 65 screws.

2. In a flanging-clamp, the combination with a pair of end standards, having forked or bifurcated upper ends, of a lower clamp-section having its ends immovably secured within 70 the upper ends of the standards, and recessed on their upper surfaces; an upper clamp-section formed with open slotted ends and communicating under side recesses, having vertical movement in the forked upper ends of the 75 standards; bell-crank levers pivoted to said end standards, the lower arms of said levers normally resting in the said recesses in the clamp-section ends, and the upper arms of said levers normally extending into the open slot- 80 ted ends of the upper clamp-section; foot-levers and screws projecting outwardly from said upper lever-arms through the said open slotted ends of the upper clamp-section; and handle-nuts on said screws. 85

3. In a flanging-clamp, the combination with a pair of end standards, having forked or bifurcated upper ends, and a series of transverse registering bores therethrough, the bores on one side being partly closed by semi- 90 annular stops, of a lower clamp-section immovably secured to said end standards; an upper clamp-section having open slotted and recessed ends vertically movable in the forked upper ends of the standards; transversely- 95 bored bell-crank levers located within the said forked upper ends of the standards, for raising the said upper clamp-section; screws and levers rigidly secured to and extending outwardly from the upper arms of said bell-crank 100 levers through the open slotted ends of the upper clamp-section; clamping-nuts on said screws; and pivot-bolts extending through the transverse bores of the said bell-crank levers, and through any opposed pairs of the 105 transverse registering bores in the forked upper ends of the standards, one end of each pivot-bolt being shouldered and formed with an outer semi-annular flange, and the opposite end of said pivot-bolt having a bent 110 weighted portion.

In testimony that I claim the foregoing I have hereunto set my hand, at Sheboygan, in the county of Sheboygan and State of Wisconsin, in the presence of two witnesses.

JOHN HENRY OPTENBERG.
